UNITED STATES PATENT OFFICE.

LAZARUS LOESER, OF NEW YORK, N. Y., ASSIGNOR TO HENRIETTE LOESER,
OF SAME PLACE.

SHOE-TIP.

SPECIFICATION forming part of Letters Patent No. 271,342, dated January 30, 1883.

Application filed November 10, 1882. (No model.)

To all whom it may concern:

Be it known that I, LAZARUS LOESER, of the city, county, and State of New York, have invented certain new and useful Improvements 5 in Shoe-Tips, of which the following is a specification.

This invention has reference to certain improvements in the shoe-tips for which Letters Patent have been granted to me heretofore, 10 numbered 180,607, and dated August 1, 1876; and the invention consists of certain details of construction by which the tips can be attached in a more reliable and convenient manner to boots and shoes.

15 In the accompanying drawings, Figure 1 represents a side elevation of a shoe provided with my improved tip. Fig. 2 is a bottom view of the tip drawn on a larger scale, and Fig. 3 is a vertical longitudinal section of the same 20 on line *x x*, Fig. 2.

Similar letters of reference indicate corresponding parts.

A represents my improved tip for boots and shoes, which is preferably made of leather that 25 is stamped into proper shape, but which may also be made of any other equivalent material which possesses sufficient flexibility for this purpose. To the bottom edge of the tip A is applied a stiff metallic frame or binding, B, 30 which is clinched or otherwise secured to the edge of the tip A, the shape of the binding or frame corresponding, like that of the tip, to the different sizes of boots or shoes with which the tip is to be used. The frame or binding B is 35 provided at its front part, preferably equidistant and at each side of the longitudinal center line of the tip, with backwardly-projecting spurs or teeth *b b*, which are preferably made integral with the frame or binding B, and 40 stamped out of the stock of the inner part of the same. These spurs serve to attach the shoe-tip to the boot or shoe, after it has been placed into the required position, by forcing them in

between the insole and outer sole. The ends of the frame or binding B are provided with 45 perforations *d*, through which small round beaded wire nails or pegs *e* are driven, so as to attach the ends of the tip to the boot or shoe, and secure thereby the entire tip at four or more points in a permanent and reliable manner to the boot or shoe. The small nails *d d* 50 are driven, like the spurs, into the sole or between the insole and the outer sole, so that the frame or binding B is firmly retained in the angular space formed between the upper and the sole. The frame or binding may either be japanned or nickel or silver plated, as desired, it forming in the latter case an ornamental edge frame for the tips of ladies' or other shoes which are not blackened. 55

My improved tip may be applied to boots or shoes without the aid of special tools or skilled hands, and is specially useful whenever a hole has been worn in the toe portion of the upper, which is most frequently the case with custom-made ladies' and children's shoes, which can by the use of my tip be worn for a considerably longer time. 60

Having thus described my invention, I claim as new and desire to secure by Letters Patent— 70

An improved shoe-tip of leather provided with a metallic frame or binding around its lower edge, having backwardly-projecting spurs or teeth arranged substantially as shown, for the purpose described, and provided with 75 end perforations, whereby it is adapted to be attached by pegs or nails to a boot or shoe, substantially as set forth.

In testimony that I claim the foregoing as my invention I have signed my name in presence of two subscribing witnesses. 80

LAZARUS LOESER.
